UNITED STATES PATENT OFFICE.

ROBERT B. MITCHELL, OF ALBION, MICHIGAN, ASSIGNOR TO UNION STEEL PRODUCTS COMPANY, OF ALBION, MICHIGAN.

ANCHORING ELEMENT FOR CONCRETE CONSTRUCTION.

Application filed January 26, 1927. Serial No. 163,649.

The main object of this invention is to provide an anchoring element for concrete constructions which is well adapted for the securing of floor sleepers to a concrete foundation or wall facings or the like which is very economical in structure and permits the securing of tie members at substantially any point desired.

Objects pertaining to details and economies of my invention will definitely appear from the detailed description to follow. The invention is clearly defined and pointed out in the claims.

A structure embodying the features of my invention is clearly illustrated in the accompanying drawing forming a part of this application, in which:

Fig. 1 is a fragmentary perspective view of a floor foundation provided with my improved anchoring elements, sleepers being shown in operative relation thereto.

Fig. 2 is a fragmentary perspective view of one of my improved anchoring elements.

Fig. 3 is a detail view partially in section on line 3—3 of Fig. 2 showing the manner of securing the anchoring members to the body portion of the anchoring element.

Fig. 4 is a fragmentary view illustrating my improved anchoring element as adapted for a wall facing tie.

Fig. 5 is a fragmentary perspective showing a modification in the anchoring members.

Referring to the drawing, 1 represents a concrete floor foundation or the like and 2 the sleepers. My improved anchoring element comprises a rod 3 preferably formed of wire or light rod and provided with a plurality of spaced anchoring members 4, these anchoring members being provided with 40 hook-like eyes 5 at their upper ends engaged over the rod and secured thereto in fixed relation by means of welding, as indicated at 6 in Fig. 3.

These anchoring members are preferably bent or distorted as shown so as to provide an effective anchoring hold in the cement body. The anchoring elements are positioned when the concrete is in a plastic state by pushing the anchoring members into the

concrete with the rod portion lying along the 50 surface of the concrete. When the concrete is set the rod portion may be pried up sufficiently to receive a tie wire such as indicated at 7 or a bit of the concrete chipped out under the rod to permit the passing of 55 the tie wire below the same.

The sleepers as shown in Fig. 1 may be positioned as desired, that is, in any desired spaced relation, and quickly and securely anchored.

In the adaptation shown in Fig. 4 I show one of my anchoring elements as applied to a wall 8, ties 9 being engaged therewith for anchoring the brick facing 10.

In the modification of Fig. 5 the anchoring members 11 are provided with two legs, the same being formed of pieces of wire bent to receive the rod, the bights of the anchoring members being secured in the same manner as the eyes of the embodiment described. 70

My improved anchoring elements are very economical to produce and are highly satisfactory in use, the same being convenient to handle and effective for the purpose.

Having thus described my invention what 75 I claim as new and desire to secure by Letters Patent is:

1. An anchoring element for use in concrete construction consisting of a rod and a plurality of spaced anchoring members 80 formed of wire and having eyes at their upper ends embracing said rod and welded thereto so that they are fixedly secured in spaced relation on the rod.

2. An anchoring element of the class described comprising a substantially straight rod, and a plurality of anchoring members having eyes embracing said rod and welded thereto so that the anchoring members are supported to project transversely of the rod 90 and in fixed relation thereto so that said anchoring members may be forced into a concrete body in plastic condition with the rod lying along the surface thereof.

In witness whereof I have hereunto set my 95 hand.

ROBERT B. MITCHELL.
